UNITED STATES PATENT OFFICE.

CHARLES DARWIN TISDALE, OF BOSTON, MASSACHUSETTS, ASSIGNOR TO HIMSELF AND JOSEPH HENRY CLAPP, OF SAME PLACE.

IMPROVED RAILWAY-CARRIAGE WHEEL AND AXLE.

Specification forming part of Letters Patent No. 97,994, dated December 14, 1869.

To all whom it may concern:

Be it known that I, CHARLES DARWIN TISDALE, of Boston, of the county of Suffolk and State of Massachusetts, have made a new and useful invention, having reference to railway-carriage wheels and axles; and I do hereby declare the same to be fully described in the following specification, and represented in the accompanying drawings, of which—

Figure 1 is a side elevation, and Fig. 2 a longitudinal section, of an axle and its wheels as provided with my invention. Fig. 3 is a top view, and Fig. 4 a longitudinal section, of the axle. Fig. 5 is a transverse section of one of the wheels.

On May 25, 1869, Letters Patent No. 90,410 were granted to myself and Joseph H. Clapp on an invention made by me, the same mainly consisting in the combination and arrangement of two wedge-keys, a stop-piece, and grooves in the wheel-hub and axle, the whole being substantially as exhibited in the specification and drawings of such patent.

My present improvement has particular reference to the stop-piece of such combination, which stop-piece I provide with a screw, to force it backward as it may become worn. The said stop-piece I make sometimes in one and sometimes in two pieces, the screw-shank in the latter case going through both parts, as hereinafter explained. When made in two parts, the stop-piece admits of one or more washers or thin plates of metal being arranged between the parts and on the shank of the screw in case of wear of the stop-piece and of it being desirable to extend it lengthwise at any time.

In the drawings, A denotes the axle, and B its two wheels; b b', the wedge-keys; a a and o o, the grooves of the axle and wheel-hubs

for the reception of the wedge-keys. The stop-pieces of the grooves of the axle and the wedge-keys are shown at c c.

Between one of the inner wedges and its stop-piece is a capstan-screw, d, which is screwed into the wedge, and has its head abutting against that end of the stop-piece which is next to the next adjacent wheel. On turning back the screw the wedge will be forced into the wheel, and the stop-piece will be pressed back against the inclined inner end of the groove a. The head of the screw may have a series of holes made diametrically through it, to enable a person, by means of a pin, to revolve the screw as occasion may require.

The drawings also represent the screw at d' as screwed into and through the stop-piece and extended into a small hole or cavity, e, in the inner edge. The stop-piece is shown as made in two separate parts, f f', the screw going through both, but being screwed into the rear one, f, only. By turning up the screw the stop-piece, or its rear part, will be forced backward into the groove, and the wedge will be driven forward into the wheel. The stop-piece may be made in one solid piece; but in case it may be preferable to have it in two pieces, f f', as described, it may be so constructed.

I claim—

The combination of the tightening-screw d or d', or its equivalent, with the wedge-keys b b', the grooves a o, (in the wheel, hub, and axle,) and the stop-piece c, substantially as described.

CHARLES DARWIN TISDALE.
